SHORT WOOD CHAIN BARKER

Herbert W. Guettler, San Francisco, Calif.

Application October 8, 1949, Serial No. 120,304

7 Claims. (Cl. 144—208)

1

My invention is concerned with a device for removing the bark from relatively short pulp wood logs or the like.

More particularly my invention is directed to a novel type of barking machine in which the barking process is largely accomplished by the attritional action between the logs themselves.

The presently employed method of barking short logs employs a system of feeding logs into a large open ended cylindrical drum where they are tumbled against the interior of the drum by revolving action thereof. The drum is normally filled about half way and as the drum revolves the logs cascade down the surface of the wood piled therein. Under this system the majority of the logs in the wood pile fail to move relative to one another, only the top layer of logs moving as a rule. Such a method is slow, expensive and requires large cumbersome machinery.

Another method in present use in the industry is one in which the logs are corded parallel to one another in a stationary vat; cams, wheels or chains in the bottom of the vat causing the logs to move one against the other.

Briefly my invention accomplishes the bark removal process through the use of a large stationary vat having a specially formed bottom and a plurality of chains moving thereacross for tearing the bottom layer of logs piled in the vat away from one another to cause a constant turbulation effect. Such a churning action causes most of the logs to move relative to one another so that the bark is speedily removed by the attritional or frictional action between the moving logs.

The main object of my invention is to provide a new and improved log barking machine in which the bark removal process is accomplished by attritional action between the logs.

Another object of my invention is to provide a new and cheaper bark removal machine in which the logs are piled "hit and miss" with no fixed pattern, to increase the bark removing attritional action of the logs.

Still another object of my invention is to provide a new and improved bark removing apparatus which is adapted to accomplish continuous and quick bark removal.

These and other objects will appear from time to time as the following specification and description proceed. In order to acquaint those familiar with this art with the mode of constructing and utilizing my invention, I shall describe a certain preferred embodiment thereof with reference to the accompanying drawings wherein:

2

Figure 1 is a view partly in section and partly in side elevation of a machine embodying my invention;

Figure 2 is a front view of the machine shown in Figure 1, with the log moving chains removed;

Figure 3 is an enlarged partial top plan view of the bottom of the vat showing the arrangement of the bark removal openings in the V-shaped ribs running therealong;

Figure 4 is a fragmentary sectional view, on an enlarged scale, taken substantially on line 4—4 of Figure 1; and

Figure 5 is a fragmentary side view on an enlarged scale, of one of the log agitating chains.

Referring now to Figures 1 and 2 of the drawings, the barking machine 10 shown therein comprises a feed conveyor 11 which dumps logs 12 into a barking vat 13. The vat 13 is supported by a suitable upright frame structure 14 and has a guide chain assembly 15 along an inclined bottom 16 thereof and means for agitating the logs and guiding them upwardly to a discharge apron 17 from whence they slide downwardly to a discharge conveyor 18, to be carried away from the barking machine. The removed bark may be received in a hopper 19 positioned below the vat 13 and is carried away by a bark conveyor 20, as will appear more fully later.

With particular reference to Figure 2 of the drawings the feeding conveyor 11 shown therein is comprised generally of a link chain 25 threaded over suitable sprockets 26 mounted on shafts 27 which in turn are carried by suitable side plate framing members 28 secured at one end to the upright frame 14 of the machine. The chain 25 may have suitable engaging lugs 29 secured thereto at spaced intervals for engaging logs 12 to move them upwardly into the vat of the machine. A V-shaped guide chute 30 having side members 31 may be mounted on the side plate members 28 to maintain the logs in contact with the conveyor chain 25.

The barking vat 13 as shown in Figures 1 and 2 comprises generally infeed and outfeed side plates 34 and 34' of materially different heights and operatively connected with a long upright end plate 35 positioned at the forward end of the machine and with a shorter but higher back end plate 36 positioned at the rear of the machine. The bottom 16 extends between and joins the two end plates 35 and 36, and slopes upwardly from front to back as seen clearly in Figure 1. In construction the end plates are formed as a continuous part of the bottom plate structure to form an enclosed vat construction. The vat itself with

the several plates and bottom referred to above is suitably supported by the upright framing 14 which comprises generally a series of four upright beams 38 cross connected at the forward and back sides of the machine by suitable cross beams 39 and at the sides of the machine by I beams 40, all joined together to form a rigid framing.

The bottom construction is composed, as shown herein in Figure 3, of a plurality of V-plates 41 having their apexes 42 extended upwardly and their lower edges secured to a plurality of bed plates 43 which are relatively narrow. The bed plates 43 are suitably separated leaving channeled openings 44 below which chain guides 45 may be mounted. The V-plates 41 are provided with a plurality of bark removal openings 46 positioned at various alternating positions along the entire bottom construction.

The chain guides 45 are herein shown as comprising a pair of channel beam members 47 mounted below the bed plates in separated relation with one another and having L-shaped angle irons 48 secured thereto, for purposes of receiving the guide chain assembly 15 thereon for rolling movement, as will appear presently. A chain guide return assembly 49 is mounted below and secured to the chain guide 45 and is composed of similar channel and L-shaped angle irons as clearly appears in Figure 4 of the drawings. One such set of chain guides 45 and 49 is mounted in registering relation below each of the openings or separations 44 created by the spaced bed plates 43 in the bottom of the vat, for receiving therein the guide chain assembly 15.

The guide chain assembly 15 is comprised of a plurality of individual link type chains 52 threaded over driving sprockets 53 mounted at the upper back side of the machine on the framing 14, by means of a shaft 54 housed in bearing supports 55 for rotational movement therein. Suitable rotative means, such as a motor (not shown), may be employed to drive the drive sprockets 53, to cause movement of the guide chains 52. Idler sprockets 56 may be mounted at the lower end of the guide chain assembly near the lower front end of the machine. The idler sprockets may be rotatably mounted on suitable shafts 57 carried by bearing support members 58 and secured to suitable standards 59 similar to the drive sprocket assembly described above. As herein shown in Figure 2, three such link chains 52 are utilized in the bottom of the vat for moving the logs upwardly along the vat's bottom, as will appear later herein under the use and operational description. It is obvious that a greater or lesser number of such guide chains may be utilized in the chain assembly 15, depending on the size of vat structure used. The guide chains 52 mesh with the driving and idler sprockets and fit into the separations 44, as explained above, and may comprise, as shown herein, a link construction having a series of triangular shaped lugs 60 in which the front face 61 thereof is formed at a relieving angle, so that when a lug comes out of the wood pile, logs 12 will not be carried upwardly out of the vat. Intermediate pairs of links 62 are spaced at one end by a sleeve 64, and are connected to spaced arms 67 on each lug 60 by means of a pivot pin 63 passing through the sleeve and the spaced links and arms, the pin 63 having guide rollers 65 mounted at its outer ends, as is shown in Figure 4, and the rollers 65 being located outside of the spaced arms 67. The intermediate links may be interconnected by additional pivot pins 68 similar to pins 63 to com-

plete the link assembly of the chain 52. When the guide chains 12 are moved along the bottom 16 of the vat with the lugs 60 projecting upwardly through the openings 44 between the bed plates 43, the logs will be carried upwardly along the bottom to a position opposite a suitable discharge apron 17. To aid in pushing the logs up the inclined bottom structure, the chain lugs 60 may be provided optionally with a pair of scraper blades 69 projecting laterally therefrom and positioned at the lower end of the relieved face 61 thereof in a position so that their lower edges contact the upper surfaces of the bed plates 43 to insure a scraping action thereacross.

The discharge apron 17 is herein shown in Figure 1 as an angularly disposed metal plate extending laterally from one lower side plate member 34' of the vat 13, at a point diagonally opposite the feed conveyor 11, and adapted to receive the logs, conveyed upwardly by the link chains 52, for sliding movement therealong in a downward direction to be loaded onto a conventional belt type discharge conveyor 18. A side board member 10 may be positioned angularly along the discharge conveyor 18 opposite the lower end of the apron 17 to prevent the logs from spilling off of the conveyor.

The discharge conveyor 18, as herein shown, is a conventional belt type conveyor comprising a continuous flexible belt 72 mounted over a series of drums 73 rotatably supported on suitable shafts 74 carried by bearing members 75 which are secured to upright standards 76 mounted on an angular supporting frame construction 77 extending laterally from the side plate 34' of the vat, and positioned below the discharge apron 17. Other supporting means (not shown) may be employed to support the discharge conveyor at various points removed from the machine.

Removal of the bark from the bottom interior of the vat is permitted by the slots or openings 46 formed in the V-plates 41 of the vat bottom. As the bark is removed by the attritional action of the many logs with one another it falls downwardly through the openings 46 to be received by a cone shaped hopper 19 having side members 80 disposed angularly downward in conical or pyramidal relation. The top and bottom of the hopper 19 of course are open to allow free passage of the falling bark to the bark conveyor 20.

The bark conveyor 20 is herein shown as a conventional belt conveyor, similar to the discharge conveyor 18, and has a plurality of drums 81 rotatably supported on shafts 82 carried by bearing members 83 which are supported by suitable standards 84. A hanger construction 85 supports the bark conveyor below the hopper 19 and may comprise, as shown herein, side members 86 and a supporting bottom plate 87 all preferably of metal suitably secured together, as by welding, to form a rigid structure.

Use and operation

In utilizing the machine such as I have described above, the logs, preferably six feet in length or under, are brought to the barking vat by the feed conveyor and dumped hit or miss into the vat where they are engaged by the guide chain lugs projecting upwardly from the bottom of the vat. The guide chains are moved constantly upwardly along the inclined surface of the bottom of the vat by means of the drive sprockets and return outside of the vat bottom to roll around the idler sprockets positioned at the front of the machine. Such movement of the guide chains

causes the bottom layer of the logs dumped into the vat to be torn away from the pile thus causing a turbulation and tumbling movement of the logs in the pile which brings about attritional barking action therebetween. It should be noted that the vat bottom comprises a plurality of V-shaped plates between which the guide chains and the projecting lugs move. Such a V-shape bottom construction eliminates dead spots between the chains and causes the logs to roll down the sloping sides of the V-shaped plates to be engaged by the lugs on the guide chains whereby they may be conveyed upwardly along the sloping bottom of the vat. Due to the insured movement of the logs relative to one another, under my system of barking, the bark is removed speedily and the logs come out of the top of the vat cleaned and ready to be dumped over the lower side plate 34' onto the apron from whence they roll downwardly to be engaged by the discharge conveyor and carried away from the machine. It should be noted that the forward face 61 of each triangular lug 60 is relieved or disposed angularly inward so that as the chain moves out of the vat's interior and over the driving sprockets, the logs are not carried out of the vat but are allowed to slide off of the engaging lugs and back into the pile. The bark removed from the logs within the vat falls through the openings 46 into the bark receiving hopper 19, and then moves downwardly onto the bark conveyor which carries it away from the machine. If any of the logs are not properly barked they may be picked off of the discharge conveyor by inspectors and placed on a return conveyor, not shown, to be loaded again on the feeding chain conveyor 11, and the barking process, repeated.

Thus, it may be seen that I have provided a new and useful type of short wood barking machine in which the bark is readily removed by the turbulation and erratic movement of the logs causing attritional removal of the bark. Also, my machine is of a cheaper construction than presently employed in the field and has been found to be a successful and rapid bark remover.

While I have herein shown and described one form in which my invention may be employed, it will be readily understood that substitution of equivalents, modifications and various changes may be employed without departing from the spirit and scope hereof, and, therefore, I do not wish to be limited to the specific embodiment displayed herein, except as may appear in the following appended claims.

I claim:

1. In a wood barking device for removing bark from pulp wood logs or the like by attritional movement of the logs against one another, a stationary barking vat having parallel, spaced apart end and side walls, an upwardly sloping bottom and an open top, log feeding means for dropping logs into said vat and over the lower end of said inclined bottom thereof, a plurality of continuous looped chains mounted in parallel spaced relation in channeled openings in said vat's bottom, said chains entering said vat through the bottom thereof adjacent the foot of its slope; driving means for causing said chains to move upwardly along the slope of said bottom and thence vertically upward over one of the end walls, a plurality of triangular cross sectioned ribs positioned in parallel spaced relation and constituting said sloping vat bottom between said chains and channeled openings, and said triangular ribs having their apical top edges projecting upwardly into

said vat's interior whereby said logs piled in said vat will be guided down the sloping sides thereof and onto said log engaging chains to be carried to the upper end of said sloping bottom for their eventual discharge from said vat over one of said side walls thereof.

2. In a wood barking device for removing bark from pulp wood logs or the like by attritional movement of the logs against one another, a stationary barking vat having an upwardly sloping bottom, two end walls and first and second side walls of which said first side wall is of greater height than said second side wall, log feeding means above the lower end of said sloping bottom for maintaining said vat substantially full of logs, a plurality of continuous looped chains mounted in parallel spaced relation in channeled openings in said vat's bottom, a plurality of upwardly projecting lugs mounted on said chains, driving means for causing said chains and said lugs to move upwardly along the slope of said bottom and one of said end walls, an apron mounted along said second side wall of said vat, extending outwardly and downwardly from an upper edge thereof, over which said logs will slide after they have been carried upwardly along said bottom's incline and said one end wall by said chains and lugs and brought opposite the upper edge of said apron, with said movement of said logs in contact with said lugs and said chains causing abrasive relative movement of said logs piled in said vat whereby said bark is removed therefrom.

3. In a log barker, a vat substantially rectangular in plan having two parallel spaced side walls, one of which is of materially greater height than the other, and having a bottom wall inclined upwardly from one end wall and merging into the opposite end wall, a plurality of log engaging lugs projecting above said bottom wall and traveling upwardly therealong and along said opposite end wall, means for delivering logs to said vat over said one higher side wall adjacent said one end wall thereof, and means for discharging logs from the vat over said other side wall and adjacent said other end wall.

4. In a log barker for removing bark from pulp wood logs or the like by attritional movement of the logs against one another, a stationary barking vat comprising opposite side and end walls, and a bottom wall extending between the side walls and sloping upwardly from one end wall toward, and merging into, said other end wall, one of said side walls being of materially greater height than said other side wall; log feeding means for discharging logs into said vat in hit or miss relation over said one higher side wall adjacent said one end wall, a plurality of parallel spaced log propelling and agitating chains traveling over said bottom wall toward and upwardly along said other end wall, and a discharge apron adjacent said other end wall, and sloping outwardly and downwardly from said other lower side wall, said vat and chains co-operating to turbulently agitate said logs and discharge them in a cleaned condition over said apron.

5. In a log barker, a stationary vat, substantially rectangular in plan, having a bottom wall inclined upwardly from one end wall and merging into a second opposite end wall, and having a pair of spaced and opposed side walls interconnecting said two end walls, one of said side walls being of materially greater height than

the other; means for delivering logs to said vat over said higher side wall and adjacent said one end wall, and a plurality of log engaging lugs entering said vat at the foot of said inclined bottom thereof and projecting above said bottom wall; said lugs traveling in parallel paths upwardly along the slope of said bottom wall from said one end wall to said second end wall and thence vertically upwardly along the latter end wall, the leading edges of said lugs being so disposed as to incline downwardly and inwardly of said vat in the vertical travel thereof along said second end wall; said lugs serving to constantly agitate said logs in said vat to cause attritional removal of the bark therefrom and to move logs lying adjacent said bottom wall from said one end wall toward and upwardly along said second end wall with said logs disengaging from said lugs and falling away from said second end wall back into said vat during 20 said upward travel thereof due to said downward incline of said lugs, barked logs being discharged from the top of the pile of logs within said vat over said lower side wall adjacent said second end wall.

6. In a log barker, a stationary open top vat comprising side and end walls and a bottom wall extending from one end wall at an upward inclination toward and merging into the other and opposite end wall, and log propelling and agitating chain means entering said vat through the bottom thereof and traveling along said bottom wall toward and upward along said other end wall, said chain means having upwardly projecting substantially triangular lugs effective 35 for engaging logs and moving them along said bottom and said other end wall and directing them from the latter wall back into said vat, one of said side walls being of materially less height than the other side wall and said other 40

end wall adjacent the latter for discharge of barked logs over said one side.

7. In a log barker, a stationary open top vat comprising side and end walls and a bottom wall extending from one end wall at an upward inclination toward and merging into the other and opposite end wall, and log propelling and agitating chain means entering said vat through the bottom thereof and traveling along said bottom wall toward and upward along said other end wall, said chain means having upwardly projecting substantially triangular lugs effective for engaging logs and moving them along said bottom and said other end wall and directing them from the latter wall back into said vat, one of said side walls being of materially less height than said other end wall adjacent the latter for discharge of barked logs over said one side wall.

HERBERT W. GUETTLER.
